UNITED STATES PATENT OFFICE

165,700

BABY BUNTING

Gertrude Schwartz, Chicago, Ill.

Application February 7, 1951, Serial No. 14,122

Term of patent 14 years

(Cl. D92—2)

To all whom it may concern:

Be it known that I, Gertude Schwartz, a citizen of the United States, residing at Chicago, in the county of Cook, and State of Illinois, have invented a new, original, and ornamental Design for a Baby Bunting, of which the following is a specification, reference being had to the accompanying drawing, forming a part thereof, in which:

Fig. 1 is a perspective view of a baby bunting embodying my new design.

Fig. 2 is a top plan view of the baby bunting shown in Fig. 1 as it appears in unfolded and spread out position, the tie ribbons being shown broken.

The back of the bunting is plain.

The dominant feature of my design resides in the combination on the baby bunting disclosed

of the full size hood portion having a turned up front cuff, in association with a pair of relatively wide tie ribbons, all as shown.

I claim:

The ornamental design for a baby bunting, substantially as shown and described.

GERTRUDE SCHWARTZ.
